(57) **CLAIM**

The ornamental design for a push up trainer, as shown and described.

DESCRIPTION

FIG. 1 is a front perspective view of the push up trainer, showing the overall new design.

FIG. 2 is a side view of the push up trainer, with a user shown in broken lines.

FIG. 3 is a side view of the push up trainer, with a user shown in broken lines; and,

FIG. 4 is a side view of the push up trainer, with a two additional stacked push up trainers shown in broken lines.

The broken line portions of the disclosure are for environmental purposes only and form no part of the claimed design.
